CLAIM

The ornamental design for a combined suitcase and self standing tool holding pegboard, as shown and described.

DESCRIPTION

FIG. 1 is a front, top and left side perspective view of a suitcase for a self-standing tool-holding pegboard showing my new design;

FIG. 2 is a left end elevational view, the right end is a mirror image thereof;

FIG. 3 is a top plan view thereof;

FIG. 4 is a bottom plan view thereof;

FIG. 5 is a left side view;

FIG. 6 is a right side view;

FIG. 7 is a top view showing the suitcase in its opened state;

FIG. 8 is a fragmentary top perspective view of a suitcase with the lid in an open position;

FIG. 9 is a left end view of the suitcase in its opened state and showing the removed pegboard; and,

FIG. 10 is a front perspective view thereof in an open position, the pegboard is shown separately for clarity of illustration.
